UNITED STATES PATENT OFFICE

133,691

DESIGN FOR A TABLE

Harold G. Arnold, Wooster, Ohio, assignor to Toy
Craft, Inc., a corporation of Ohio

Application September 5, 1941, Serial No. 103,181

Term of patent 3½ years

To all whom it may concern:

Be it known that I, Harold G. Arnold, a citizen of the United States, residing at Wooster, in the county of Wayne and State of Ohio, have invented a new, original, and ornamental Design for a Table, of which the following is a specification, reference being had to the accompanying drawing, forming a part thereof.

Fig. 1 is a top plan view of a table, showing my design; and

Fig. 2 is a side elevational view thereof.
The drawing has been shaded in Fig. 1 to represent contrastingly colored areas.

I claim:

The ornamental design for a table, as shown and described.

HAROLD G. ARNOLD.

CERTIFICATE OF CORRECTION.

Design No. 133,691.

September 8, 1942.

HAROLD G. ARNOLD.

It is hereby certified that error appears in the above numbered patent requiring correction as follows: In the grant, lines 2 and 12, and in the heading to the printed specification, lines 3 and 4, for "Toy Craft, Inc." read --Toy Kraft, Inc.--; and that the said Letters Patent should be read with this correction therein that the same may conform to the record of the case in the Patent Office.

Signed and sealed this 3rd day of November, A. D. 1942.
